FIRE EXTINGUISHING METHOD AND
MEDIUM

Heinrich Bertsch, Chemnitz, Germany, assignor,
by means assignments, to Böhme Fettchemie-
Gesellschaft mit beschränkter Haftung, Chem-
nitz, Germany

No Drawing. Application November 16, 1934, Se-
rial No. 753,406. In Germany November 16,
1933

12 Claims. (Cl. 23—11)

This invention relates to fire extinguishing agents and more particularly to the foam producing type of fire extinguishing medium, whereby the combustible material may be smothered by a blanket of foam. It is the principal object of the invention to provide a medium of this character which is inexpensive to produce and which will be effective for the extinguishing of fire in materials not readily controlled by fire extinguishing media heretofore developed.

Thus it is a further object of the invention to provide a medium which will foam freely and which will effectively blanket and smother the combustion of alcoholic fluids. It is a feature of the invention that the medium forms a foam in which the gaseous agent is principally air, prior air foam producing media being rendered ineffective by the alcohols.

It is a more specific object of the invention to provide a fire extinguishing medium comprising a mixture of a fluid with a quaternary high molecular ammonium salt or the corresponding phosphonium and sulphonium compounds. Quaternary high molecular ammonium salts, which contain long aliphatic chains or cycloaliphatic or aromatic radicals as substituents, are found to produce a dense foam film, completely stable to alcohols, and indestructible even when contacted with the hot walls of a tank containing burning alcohol, affording a positive guaranty of rapid and complete extinction of all fires in liquids and particularly in liquids of an alcoholic character.

The extinguishing of alcoholic fires by chemical foam producing methods, for instance by the development of a foam blanket in which the gas phase of the foam consists of carbon dioxide or other noncombustible gas, are not only defective and dangerous but very expensive. In accordance with the present invention fires can be effectively extinguished by means of air foam produced by an ordinary foam generator or foam pipe.

Example 1

A solution of 500 grams of lauryl pyridinium sulphate in 100 liters of water is discharged in any convenient manner into a tank containing burning alcohol. The fire is promptly extinguished without the evolution of obnoxious or dangerous gases.

In lieu of lauryl pyridinium sulphate there may be employed compounds with higher or lower alkyl residues, preferably having from 8 to 22 carbon atoms, or substitution products of these

compounds, containing for instance amino groups, halogen atoms, ester groups, or ether groups in the aliphatic chain. Similarly, quaternary ammonium compounds which are not derived from heterocyclic nitrogen bases, but from aliphatic, cyclo-aliphatic, aromatic, or even mixed tertiary amines, as well as the corresponding phosphonium and sulphonium compounds, may be employed.

While the quaternary high molecular ammonium compounds and particularly those derived from heterocyclic nitrogen bases, such as pyridin for example, are of special importance by reason of the fact that they are readily accessible, numerous other compounds of the character hereinbefore indicated have been found effective. Thus the following specific compounds, and the fluid mixtures and aqueous solutions thereof, will produce a dense blanket of foam suitable for the extinguishing of fires, especially fires of an alcoholic origin:

Tetradecyl, hexadecyl, and octa-decyl pyridinium sulfate, undecenyl, dodecyl, tetradecyl, octadecyl, octadecenyl chinolium sulfate, decyl pyridinium bromide, hexadecenyl chinolinium iodide, quaternary ammonium compounds derived from asymmetrical oleyl-diethyl-ethylenediamine by addition of dimethyl sulfate or diethyl sulfate or methyl iodide, decyl phosphonium iodide, dodecyl phosphonium bromide, tetradecyl phosphonium bromide, octadecenyl phosphonium iodide, dodecyl sulphonium iodide, octadecyl sulphonium bromide, heptyl-*i*-urea bromide, decyl-*i*-thiourea iodide, hexadecyl-*i*-thiourea iodide, the addition products of tetradecyl bromide or dodecyl iodide to hexamethylenetetramine, heptyl guanidine, tolyl guanidine, the quaternary ammonium compound prepared by the addition of the dodecyl ether of α -glycerine bromhydrine $C_{11}H_{23}CH_2O.CH_2.CHOH.CH_2Br$ to pyridin, the quaternary ammonium compound formed by the addition of bromine-acetic acid dodecyl ester $Br-CH_2COO.CH_2.C_{11}H_{23}$ to chinoline.

Example 2

45

A solution of 600 grams of hexadecyl triethyl phosphonium bromide in 100 liters of water mixed with 10 liters of glycerol is discharged by a foam generator onto the burning object.

50

Example 3

55

A solution of 500 grams decyl dimethyl sulphonium iodide in 100 liters of water is discharged by a foam pipe onto the burning object.

Example 4

500 grams of the quaternary ammonium compound prepared by the addition of the hexadecyl ether of α -glycerine chlorhydrin to pyridin are dissolved in 500 liters of water and this solution is mixed with 500 liters of carbon tetrachloride. The mixture is discharged onto the burning object by a foam generator.

10 Other, preferably non-combustible liquids than water can be mixed with or employed as a solvent for the active medium, for instance carbon tetrachloride, perchlorethane and like halogenated hydrocarbons. Additions of alcohols, especially of glycerol, are often suitable for preventing freezing of the fire-extinguishing agents at low temperatures.

15 Having thus described the invention, what is claimed as new and desired to be secured by Letters Patent is:

20 1. A method of extinguishing fire in alcoholic material which comprises covering the burning material with foam produced by a mixture of liquid and a compound selected from the group consisting of high molecular quaternary ammonium, phosphonium and sulphonium compounds.

25 2. A method of extinguishing fire in alcoholic material which comprises covering the burning material with foam produced by a mixture of water and lauryl pyridinium sulphate.

30 3. A fire extinguishing medium comprising a mixture of liquid and a compound selected from the group consisting of high molecular quaternary ammonium, phosphonium and sulphonium compounds.

35 4. A fire extinguishing medium comprising a mixture of water and a compound selected from the group consisting of high molecular quarter-

nary ammonium, phosphonium and sulphonium compounds.

5 5. A fire extinguishing medium comprising a high molecular quaternary ammonium compound selected from the group consisting of pyridinium, quinolinium, and isoquinolinium salts.

6. A fire extinguishing medium comprising a solution of a quaternary ammonium salt of the general formula

wherein R is an aliphatic radical containing not less than eight carbon atoms in a continuous chain, X is a halogen atom or $-\text{OSO}_3\text{H}$ or $-\text{NO}_3$ and NR_2 is a pyridine or a quinoline. 15

7. A medium for extinguishing fire comprising an aqueous solution of a substance selected from the group consisting of high molecular quaternary ammonium, phosphonium and sulphonium compounds. 20

8. A fire extinguishing medium comprising an aqueous solution of a high molecular quaternary ammonium compound.

9. A fire extinguishing medium comprising an aqueous solution of a pyridinium salt. 25

10. A fire extinguishing medium comprising an aqueous solution of lauryl pyridinium sulphate.

11. A method of extinguishing fire which comprises producing a combustion smothering foam with a mixture of water and a pyridinium compound. 30

12. An alcoholic combustion extinguishing mixture comprising water and a foam producing medium including a quaternary ammonium compound selected from the group consisting of compounds derived from aliphatic, aromatic and mixed tertiary amines. 35
